CLAIM

The ornamental design for a bottle, as shown and described.

DESCRIPTION

In a preferred embodiment the bottle is useful for containing and dispensing cleaning products, most preferably a liquid drain cleaner.

FIG. 1 is a right, top, front perspective view of a first embodiment of a bottle showing our new design;

FIG. 2 is a front elevational view thereof, the rear elevational view being a mirror image thereto;

FIG. 3 is a left side elevational view thereof;

FIG. 4 is a right side elevational view thereof;

FIG. 5 is a top plan view thereof;

FIG. 6 is a bottom plan view thereof;

FIG. 7 is a right, top, front perspective view of a second embodiment of the bottle;

FIG. 8 is a front elevational view thereof, the rear elevational view being a mirror image thereto;

FIG. 9 is a left side elevational view thereof;

FIG. 10 is a right side elevational view thereof;

FIG. 11 is a top plan view thereof; and,

FIG. 12 is a bottom plan view thereof.

The broken line representations of neck finish in FIGS. 1-5, and a level indicator in FIGS. 3 and 6, are for purposes of illustration only and form no part of the claimed design.
